UNITED STATES PATENT OFFICE

2,478,100

RAIN WATER CONDUCTOR BRACKET

Harry H. Histand, Doylestown, Pa.

Application October 29, 1947, Serial No. 782,923

1 Claim. (Cl. 248—48.2)

1

This invention relates to a supporting bracket for down spouts or drain pipes.

An object of this invention is to provide an improved bracket or support for drain pipes which are secured to the outer side of a building, and provides an improved means whereby the pipe will be firmly supported by substantially concealed brackets.

Another object of this invention is to provide an improved bracket which is engaged with the lower end of an upper pipe section, for supporting the upper pipe section, the bracket being secured at a point below the upper pipe section and concealed by the succeeding pipe section.

A further object of this invention is to provide a bracket of this kind which can be constructed out of a flat strip of metal which may be nailed or otherwise firmly secured to the outer side of the building.

With the above and other objects in view, my invention consists in the arrangement, combination and details of construction disclosed in the drawings and specification, and then more particularly pointed out in the appended claim.

In the drawing,

Figure 1 is a detail rear elevation, partly in section, of a bracket constructed according to an embodiment of this invention,

Figure 2 is a sectional view taken on the line 2—2 of Figure 1,

Figure 3 is a fragmentary sectional view taken on the line 3—3 of Figure 2,

Figure 4 is a detail front elevation of the bracket.

Referring to the drawing, the numerals 10 and 11 designate generally a pair of drain pipe sections which are telescopically connected together. In order to provide a means whereby the pipes may be suspendingly supported from the outer side of a building designated B, I have provided a bracket which is formed out of a single strip of flat material. The bracket generally designated as 14 comprises a base strip 15 which is formed with a plurality of vertically spaced apart horizontal elongated slots 13. Nails 16 are adapted to be extended through selected ones of the slots 13 so that the plate 15 will be firmly secured to the outer side of the building B.

The lower end of the plate or strip 15 has extending right angularly therefrom a pair of tangs or points 17 which are adapted to be driven into the side of the building B. The strip or plate 15 has extending from the upper end thereof a right angularly disposed supporting arm 18, and the arm 18 has depending therefrom a hook 19. The hook 19 includes a shank 20 which is formed with an upwardly extending bill 21. The shank 20 is adapted to be interposed between the telescoping portions of the pipe sections 11 and 12, as shown

2

in Figure 2, and the bill 21 is adapted to be extended underneath the lower end of the pipe section 11 and upwardly interiorly of this pipe section.

5 The hook 19 is slightly narrower in width than the supporting arm 18 so as to thereby form a pair of outwardly extending lugs 22 which are adapted to engage the outer side of the pipe section 11 and cooperate with the hook 19 in tightly holding the pipe section 11 to the supporting arm 18.

In the use of this bracket, the upper pipe section 11 is initially engaged with either the down spout nipple or other portion of the gutter and 15 the hook 19 is engaged with the lower end of the pipe section 11. This latter section is held in its proper position and the base plate or strip 15 is then nailed to the outer side of the building B by the nails 16. The points or tangs 17 are also 20 driven into the side of the building so that the plate or strip 15 will be disposed flat against the side of the building.

The succeeding or lower section 12 may then be pushed upwardly about the section 11 and also 25 about the shank 20 of the hook 19. A succeeding bracket 14 may be used to support the lower end of the succeeding pipe section 12 so that the pipe sections will be firmly supported by substantially concealed supporting means positioned between 30 the pipe sections and the side of the building.

I do not mean to confine myself to the exact details of construction herein disclosed, but claim all variations falling within the purview of the appended claim.

35 I claim:

A drain pipe supporting bracket comprising an elongated flat strip formed with a series of spaced elongated openings to receive fastening means to secure the strip on the side of a building, a right-40 angular arm extending from the upper end of said strip, and a hook having a width less than the width of said arm depending from the outer end of said arm and rearwardly offset therefrom constituting forwardly extending lugs on the outer 45 end of said arm, said hook engageable with the lower end of the drain pipe, whereby the lugs on said arm will bear against the outer side of said pipe for holding said pipe spaced outwardly from the building.

50 HARRY H. HISTAND.
